his Attorney

UNITED STATES PATENT OFFICE.

JOSEPH A. RAYDER, OF PHILADELPHIA, PENNSYLVANIA.

LOUD SPEAKER.

Application filed May 7, 1924. Serial No. 711,716.

To all whom it may concern:

Be it known that I, JOSEPH A. RAYDER, a citizen of the United States, residing at Philadelphia, in the county of Philadelphia and State of Pennsylvania, have invented a new and useful Loud Speaker, of which the following is a specification.

This invention relates to loud speakers and has more particular references to devices of the character to be employed in connection with radio apparatus, the primary object being to provide a novel, artistic and useful article for the purpose had in view.

Another object is to provide an attractive loud speaker which while pleasing to the eye, is characterized by a mellowness of tone heretofore unattainable.

Other objects and attendant advantages will be hereafter explained or apparent from the following description of one practical embodiment of my invention, while the features of novelty are succinctly defined by the subjoined claims.

The accompanying drawing is a sectional elevation of a loud speaker for radio sets conventionally embodying this invention.

Referring more in detail to the drawing it will be seen that my novel loud speaker comprises a substantial base 1, of glass or other insulate material having a central cavity 2, in the underside thereof to accommodate the reproducing instrumentality 3. This reproducing instrumentality 3 is conveniently secured in place by a removable locking closure 4, and it is positioned therein co-axial with an orifice 5, affording communication with a funnel shaped trumpet 6, seating at its lower end in a counterbore 7, and provided adjacent its upper end with an external flange 8. The aforesaid base 1, it will be noted, is formed with an upstanding arcographically configured pedestal 9, having an outwardly curved lip 10, in which seats a glass flare 11; and, said flare, in turn, is afforded support at its lower end upon the external flange 8 above referred to.

Fitted on the flare 11, is a frusto-conical reticulate material light screen 12 affording support for a fine ornamental silk or other light fabric shade 13, whereby the entire device is rendered artistic and attractive to the eye. Incidentally, it is to be particularly observed that the pedestal 9 and flare 11, may be of ornate pattern, or otherwise con-

figured so as to provide a work of art with 55 a highly finished appearance.

Transversely across the top of the screen 12 I support a removable cross bar 14, having pendent therefrom a cable 15, and connected incandescent light 16, the latter being mainly functional as a diffuser for the sounds reproduced relative to the flare 11, and according to its size will be more or less so effective.

Although I have shown and described the trumpet 6 and flare 11, as a two-piece structure, it will be perfectly obvious that they may be integrally formed; and I desire it to be clearly understood that the particular embodiment of my invention shown and described is by way of example only; accordingly the right is hereby reserved to make such detail changes or variations as fairly fall within the scope of the subjoined claims.

Having described my invention what I claim is:

1. A loud speaker comprising an insulate material base adapted to house a reproducing instrumentality, an interfitted insulate material amplifying trumpet, and a screen closure supported on the trumpet mouth with incandescent diffusing means pendent therefrom.

2. A loud speaker comprising an insulate material base adapted to house a reproducing instrumentality, an arcographically configured pedestal integral with said base, an interfitted insulate material amplifying trumpet seating in the pedestal, and a reticulate screen having a fabric covering supported over the trumpet mouth with an incandescent diffusing means pendent therefrom.

3. A loud speaker comprising an insulate material base adapted to house a reproducing instrumentality, an arcographically configured pedestal integral with said base, an interfitted insulate material amplifying trumpet seating in the pedestal, a reticulate material frusto-conical screen having a fabric covering supported over the trumpet, and a removable member carried by said screen with an incandescent lamp pendent therefrom functional also as a sound diffuser relative to the trumpet.

4. A loud speaker comprising an insulate material base adapted to house a reproducing instrumentality, an arcographically configured pedestal integral with said base, an

interfitted insulate material amplifying trumpet seating in the pedestal, a reticulate material frusto-conical screen having a fabric covering supported over the trumpet, a removable member carried by said screen with an incandescent lamp pendent therefrom functional also as a sound diffuser rela-

tive to the trumpet, and means removably supporting the reproducing instrumentality within the base aforesaid.

10

Signed at Philadelphia, Pennsylvania, the sixth day of May, 1924.

JOSEPH. A. RAYDER.
